CUSHION TYPE MOTOR OPERATED
KINESITHERAPY DEVICE

Owen K. Murphy, Adamsville, Pa.

Application June 19, 1952, Serial No. 294,457

7 Claims. (Cl. 128—33)

1

This invention relates to a cushion type motor operated kinesitherapy device and more particularly to a simple and durable device of this character with an applicator having gyratory motion and in the form of a cushion that can be readily used for treatments of the human body.

This application is a companion to my copending application, Serial No. 294,458, Filed June 19, 1952, for Motor Operated Kinesitherapy Device.

As hereinafter more fully described the present invention is concerned with a cushion type of such device having a motor operated gyrator and which device can be applied to the human body. In such appliances as heretofore made, considerable difficulty has been experienced in providing an instrument which is simple, rugged and highly effective. Because of the gyratory motion, the bearings of the motor are particularly susceptible to destructive action, and undue wear on these parts leads to failures. In the device embodying the present invention a novel and simple construction is provided for mounting the entire motor unit as an entity, and with a measure of resiliency or freedom of movement which eliminates the cause of failure and at the same time provides a motion or action having both a pleasing and a therapeutic effect.

Accordingly one of the objects of the present invention is to provide a cushion type motor operated kinesitherapy device which will operate without changes in characteristics for a long period of time and which has both a pleasing and therapeutic effect.

Another object is to provide such a device which is composed of simple and low cost parts that can readily be put together.

Another object is to provide such a device in which the motor is adequately ventilated.

Another object is to provide such a device in which the parts are resiliently held under stress.

Another object is to provide such a device in which the parts are resiliently held together through the medium of the casing or cover which encloses the cushion.

Another object is to improve the operating characteristics of the cushion, this being accomplished by providing two counterpart core sections which resiliently clamp between them the motor driven applicator and which also have resilient pads interposed therebetween so that the two core sections are movable with respect to each other to a limited degree.

Other objects and advantages of the invention will be apparent from the following description and drawings in which:

2

Fig. 1 is a perspective view of a therapeutic device made in the form of a cushion which can be used to support the body of a person or can be placed against any part of the body and which contains a gyratory mechanism or applicator to cause the cushion to impart a mild massaging action to the part of the body in contact with the cushion.

Fig. 2 is a vertical longitudinal section taken generally on line 2—2, Fig. 1.

Figs. 3 and 4 are slightly enlarged vertical transverse sections taken on the correspondingly numbered lines of Fig. 2.

Fig. 5 is a wiring diagram of the electrical components.

In the form of the invention illustrated the numeral 10 represents an electrical motor having a generally cylindrical casing 11 and a motor shaft 12. A fan 13 is mounted on each end of the motor shaft 12, the blades of these fans being shaped to move the air longitudinally through the casing 11 of the electric motor for the purpose of cooling the same. Each fan includes a hub 14 from which its blades 15 radiate, and screwed into each of the fan hubs 14 is a screw 16 which projects radially and has a head 17 at its outer end. One or more weights 18 are carried by each of the screws 16, these weights being preferably of washer-like form and held against the corresponding screw head 17 by a lock nut 19. The screws 16 are arranged in substantially the same plane and to project in substantially the same direction and it will therefore be seen that these screws 16 and their weights 18 are cumulative in providing an eccentric weight on the motor shaft 12 which tends to gyrate the motor shaft and the motor as a function of its operation.

An important feature of the invention resides in the provision of a pair of rubber rings 20 surrounding each of the opposite ends of the motor casing 11. These rings are preferably cementically secured, as indicated at 22, to the motor casing and provide a resilient radial extension of the motor casing thereof.

The motor is contained within a wooden core composed of four corner blocks indicated generally at 25 and two plywood panels 26. These four corner blocks are identical in construction and hence a description of one will be deemed to apply to all four. Each of these wooden corner blocks extends lengthwise of the axis of the electric motor 10 interposed therebetween and has one longitudinal corner 28 rounded to conform to the desired rounding shape of the cushion indi-

3

cated generally at 29. The corner of each block 25 opposite its rounding corner 28 is beveled, as indicated at 30 to conform to the rubber rings 20 of the motor 10 which these beveled faces engage, as best shown in Fig. 3. At at least one end of each of these beveled corners 30 each block is recessed, as indicated at 31 to provide a housing for a rheostat 32 as hereinafter described in detail and to permit the ready circulation of air from one end of the cushion to the other end and through the motor.

The plywood panels 26 are preferably set into recesses 33 provided in the corresponding outer face of each of the blocks 25, each of these plywood panels being disposed to bridge the space between a companion pair of the wooden blocks 25 and to form a continuation of the exterior faces of these wooden blocks, as best shown in Figs. 3 and 4. Each of these plywood panels 26 also preferably engages the two rubber rings 20 surrounding the motor casing 10. At each side of the cushion the blocks 25 are yieldingly held in spaced relation by soft sponge rubber pads or blocks 35. These sponge rubber pads are compressed between the faces 36 of the wooden blocks 25 opposite the wooden panels 26 and preferably four of such rubber pads or blocks are provided one at each end of each wooden corner block 25.

The assembly as above described is surrounded by a relatively thick layer 38 of soft foam rubber, this piece of foam rubber being secured, as by a suitable cement 39, to the external faces of the corner blocks 25 and plywood panels 26. The parts of the cushion as above described are held in compressed and assembled relation by a cover 40 which is in the form of an open ended sleeve or tube of flexible material, such as a cloth, leather or plastic fabric. This sleeve exerts a compressive force on the external face of the foam rubber layer 38 and this in turn exerts a compressive force on the several wooden corner blocks 25 and plywood panels 26. This compressive force is in turn transmitted to the several sponge rubber pads 35 and is also transmitted to the rubber rings 20 surrounding the motor casing 11. It will therefore be seen that the motor 10 is held by its rubber rings 11 in compressed relation by the several wooden parts of the core of the cushion and that the gyroscopic impulses generated by the eccentric weights 18 of this motor are transmitted through its casing and through its rubber rings to the several parts of the wooden core of the cushion. It will further be seen that the two opposite flatter sides of the cushion are free to move independently of each other to the extent permitted by the sponge rubber pads 35.

The opposite ends of the cushion are completed by folding over the opposite ends of the tubular outer cover 40 and tacking, as by staples (not shown), to the ends of the four wooden blocks 25. One end of the cushion is further enclosed by a metal plate 42 the marginal part of which encases the corresponding folded over end of the tubular cover or casing 40. This metal cover is provided with a plurality of louvers 43 in register with the opening defined by the end recesses 31 of the several corner pieces 25 of the wooden core of the cushion. This end plate is shown as secured by six screws 44 to either of those two wooden corner pieces 25 connected by a common plywood panel 26. By connecting the metal plate 42 only to these two corner pieces 25 these two corner pieces 25 are

free to move as permitted by the sponge rubber pads 35 relative to the other two corner pieces 25 without interference by the end plate 42.

The end plate 42 preferably carries the rheostat 32, the adjusting knob 45 of which is arranged externally of the plate and the resistance wire 46 and rotary slide contact 48 of which are arranged inside of this plate. This end plate can also carry a manual on and off switch 49 the operating finger piece 50 of which is arranged externally of the plate and the operated mechanism, indicated generally at 51, of which is arranged on the inside of this end plate. To insure against charring of the faces of the wood surrounding and opposing the resistance wire 46 of the rheostat 32, these faces can be protected by a facing 52 of asbestos paper which can be stapled or secured in any suitable manner. As best illustrated in Fig. 4 the motor 10, on and off switch 49 and rheostat 32 are preferably in series relationship with the opposite sides of a line brought to the cushion through a two wire cord 53 having the usual plug 54.

The end of the cushion opposite the plate 42 can be enclosed by a plate 42a which is identical to the first plate 42 except that it does not carry the rheostat 32 or switch 49. Since in other respects the end plate 42a is identical to the end plate 42 and secured in the same manner, the same reference numerals have been employed and distinguished by the suffix "a" and the description is not repeated. It will particularly be noted, however, that the plate 42a has louvers 43a to permit circulation of air lengthwise of the cushion.

In the operation of the form of the invention shown, the rotation of the eccentric weights 18 on the motor shaft 12 imparts a gyroscopic movement to this motor shaft as well as to the casing 11 of the motor. This motion is transmitted through the two rubber rings 20 around the motor casing to the four corner blocks 25 of the wooden core of the cushion as well as to the plywood panels 26 forming a part of this core, these wooden parts being held in compressive relation with the rubber rings 20.

These wooden members transmit this motion through the sponge rubber layer 38 to the tubular cover 40 and to the part of the body against the cushion. It will be noted that the wooden core for the cushion is divided into upper and lower sections which are free to move with reference to each other by reason of the four sponge rubber blocks or pads 35.

Cooling of the motor is effected by air drawn in by the fans 13 on the motor shaft through, say, the louvers 43 in the end plate 42 at one end of the cushion and is discharged through the louvers 43a of the end plate 42a at the opposite end of this cushion, this air traveling through the longitudinal open ended space provided by the wooden core members and also through the casing 11 of the motor. It will be noted that the end plates 42 and 42a are fastened by screws 44, 44a only to one section or half of the wooden core of the cushion so that these plates do not impede the movement of one section with reference to the other. The speed of the motor can readily be adjusted by turning the knob 45 of the rheostat 32 and the motor can also be de-energized through manipulation of the manual switch 49, both of these control parts being mounted on the end plate 42.

It will be noted that the subject of the invention includes two generally counterpart core sec-

tions of a housing, a motor disposed within mating opposed channels in said core sections in fully spaced relation to the walls of said channels and having a relatively stationary part and rotary part and that the rotary part has a predetermined, mechanical, rotary unbalance of substantial amount well in excess of any accidental unbalance due to inaccuracy in manufacture. It will further be noted that in the invention a plurality of soft, resilient, cushion rings or elements are provided in axially spaced relation around the stationary part of the motor and are interposed under stress between the stationary part and the walls of said channels to serve as the sole and floating support between the motor and core sections whereby rotation of the unbalanced rotary part of the motor will cause a gyratory bodily movement of the motor in a relatively small, closed loop path which is transmitted through the cushion rings to the core sections, and by said core sections through the tube or layer of foam rubber to the tubular casing.

I claim:

1. A therapeutic device, comprising a pair of generally counterpart rigid core structures, a motor disposed between said core structures in fully spaced relation to the walls thereof, said motor having a relatively stationary part and a rotary part journalled in said stationary part, said rotary part having a predetermined, mechanical, rotary unbalance of substantial amount well in excess of any accidental unbalance due to inaccuracy of manufacture, soft, resilient cushion elements interposed between said stationary part and said walls of said core sections, a tube of soft, resilient cushion material embracing both of said core sections, and a tubular, flexible cover compressively embracing said tube and core sections to yieldingly urge said core sections toward each other to maintain said cushion elements under stress, said cushion elements serving as the sole and floating support between said motor and core sections, whereby rotation of said rotary part will cause a gyratory movement of said motor in a relatively small, closed-loop path which is transmitted through said cushion elements to said core sections.

2. A therapeutic device, comprising a pair of generally counterpart rigid core structures, a motor disposed between said core structures in fully spaced relation to the walls thereof, said motor having a relatively stationary part and a rotary part journalled in said stationary part, said rotary part having a predetermined, mechanical, rotary unbalance of substantial amount well in excess of any accidental unbalance due to inaccuracy of manufacture, soft, resilient cushion elements interposed between said stationary part and said walls of said core sections, a layer of soft, resilient cushion material on the outer face of at least one of said core sections, a tubular open ended flexible cover compressively embracing said layer and core sections to yieldingly urge said core sections toward each other to maintain said cushion elements under stress, said cushion elements serving as the sole and floating support between said motor and core sections, whereby rotation of said rotary part will cause a gyratory movement of said motor in a relatively small, closed-loop path which is transmitted through said cushion elements to said core sections, fastenings securing the ends of said cover to the exposed faces of said core sections, and end plates severally secured to one only of said core sections at said exposed ends of said core sections and extending over said fastenings.

3. A therapeutic device, comprising a pair of generally counterpart rigid core sections having mating, opposing central channels extending therethrough, a motor disposed in said mating channels in fully spaced relation to the walls of said channels, said motor having a relatively stationary part and a rotary part journalled in said stationary part, said rotary part having a predetermined, mechanical, rotary unbalance of substantial amount well in excess of any accidental unbalance due to inaccuracy of manufacture, soft, resilient cushion elements interposed between said stationary part and said walls of said channels, a layer of soft, resilient cushion material on the outer face of at least one of said core sections, a tubular open ended flexible cover compressively embracing said layer and core sections and with its open ends exposing the ends of said core sections from which said channels extend, said cover yieldingly urging said core sections toward each other to maintain said cushion elements under stress, said cushion elements serving as the sole and floating support between said motor and core sections, whereby rotation of said rotary part will cause a gyratory movement of said motor in a small, closed-loop path which is transmitted through said cushion elements to said core sections, fastenings securing the ends of said cover to said exposed faces of said core sections, and end plates severally secured to one only of said core sections at said exposed ends of said core sections and extending over said fastenings, said plates being provided with louvers in register with said channels.

4. A therapeutic device, comprising a pair of generally counterpart rigid core structures, an electric motor disposed between said core structures in fully spaced relation to the walls thereof, said motor having a relatively stationary part and a rotary part journalled in said stationary part, said rotary part having a predetermined, mechanical, rotary unbalance of substantial amount well in excess of any accidental unbalance due to inaccuracy of manufacture, soft, resilient cushion elements interposed between said stationary part and said walls of said core sections, means resiliently urging said core sections toward each other to maintain said cushion elements under stress, said cushion elements serving as the sole and floating support between said motor and core sections, whereby rotation of said rotary part will cause a gyratory movement of said motor in a relatively small, closed-loop path which is transmitted through said cushion elements to said core sections, end plates severally secured to one only of said core sections at opposite ends thereof, and a manual switch in series with said motor mounted on one of said end plates.

5. A therapeutic device as set forth in claim 4 wherein a rheostat in series with said motor and said manual switch is mounted on said one of said end plates.

6. A therapeutic device, comprising a pair of generally counterpart rigid core sections having mating, opposing central channels extending therethrough, each of said core sections comprising a pair of wooden corner blocks and a panel set into opposing corners of said corner blocks to form a continuation of the outer faces of said corner blocks and to form, with said corner blocks, said mating channels on the opposing sides of said core sections, a motor disposed in said mating channels in fully spaced relation to the walls of said channels, said motor having a relatively stationary part and a rotary part jour-

nalled in said stationary part, said rotary part having a predetermined, mechanical, rotary unbalance of substantial amount well in excess of any accidental unbalance due to inaccuracy of manufacture, soft, resilient cushion elements interposed between said stationary part and said walls of said channels, and means resiliently urging said core sections toward each other to maintain said cushion elements under stress, said cushion elements serving as the sole and floating support between said motor and core sections, whereby rotation of said rotary part will cause a gyratory movement of said motor in a relatively small, closed-loop path which is transmitted through said cushion elements to said core sections.

7. A therapeutic device, comprising a pair of generally counterpart rigid core structures, a motor disposed between said core structures in fully spaced relation to the walls thereof, said motor having a relatively stationary part and a rotary part journaled in said stationary part, said rotary part having a predetermined, mechanical, rotary unbalance of substantial amount

well in excess of any accidental unbalance due to inaccuracy of manufacture, soft, resilient cushion elements interposed between said stationary part and said walls of said core sections, a layer of soft, resilient cushion material on the outer face of at least one of said core sections, and a tubular, flexible cover compressively embracing said layer and core sections to yieldingly urge said core sections toward each other to maintain said cushion elements under stress, said cushion elements serving as the sole and floating support between said motor and core sections, whereby rotation of said rotary part will cause a gyratory movement of said motor in a relatively small, closed-loop path which is transmitted through said cushion elements to said core sections.
